CUSHIONED HANDLE FOR TOOLS

Frithiof P. Forss, Aurora, Ill., assignor to Independent Pneumatic Tool Co., Chicago, Ill., a corporation of Delaware

Application December 23, 1935, Serial No. 55,729

8 Claims. (Cl. 121—36)

This invention relates to cushion means for the handles of portable power actuated impact tools such as riveting hammers, chipping hammers, and the like to absorb the vibrations to 5 which the barrels of these tools are subjected when in use, and thus relieve the hand of the operator grasping the handle of the tool of such vibrations and their resultant fatigue and sting.

The cushion member, in accordance with my 10 invention, comprises a solid mass of resilient material such as live rubber vulcanized or otherwise interconnected to certain of the parts of the handle assembly and in this connection it is one of the main objects of my invention to so form 15 the handle assembly that only a few of its parts need be handled in the vulcanizing operation. Thus the latter is simplified, as it is only necessary to handle those parts of the handle assembly to which the cushion member is directly connected.

A further object of my invention is to provide 20 a metal surface between the cushion member and the pressure fluid conveying member which extends through the cushion member to prevent metal to metal contact between the handle parts when the hand grasping section of the handle assembly is bent or deflected out of axial alignment 25 with the barrel of the tool and also to prevent chafing and wear on the cushion member in the relative movement of the handle parts.

A further object of my invention is to provide 30 the cushion member with an integral flange portion as a backing for said metal wear surface to cushion axial bending of the hand grasping portion of the handle and thus relieve the main cushion member of side strains.

A further object of my invention is to provide 35 an oil seal to prevent the cushion member from being damaged or injured by lubricant in the barrel or carried into the barrel of the tool with the incoming pressure fluid.

The invention consists further in the features 40 hereinafter described and claimed.

In the accompanying drawing:

Fig. 1 is a longitudinal sectional view with parts 45 in elevation of a pneumatic hammer provided with a cushioned handle in accordance with my invention;

Fig. 2 is an elevational view of the portion of 50 the handle adjacent the cushion;

Fig. 3 is a cross sectional view taken on line 3—3 of Fig. 1; and

Fig. 4 is a perspective view of the cushion member.

In the drawing, 1 indicates the barrel of the

tool and 2 indicates the piston or impact element reciprocably mounted in the barrel. 3 indicates the valve block at the inner end of the barrel. Said valve block seats against the end of the barrel and is keyed thereto by one or more dowel pins 5 4 as shown. The block contains a plate valve 5 for controlling the supply of pressure fluid such as compressed air to the opposite ends of the barrel to reciprocate the piston 2. The porting arrangement in the valve block and in the barrel 10 and the operation of the plate valve are similar to that disclosed in the Reinhold A. Norling Patent No. 1,881,886 granted October 11, 1932. As in said patent, the plate valve is shifted laterally in a chamber in the block by the action of the 15 pressure fluid on its opposite sides to open and close the ports to the opposite ends of the barrel. The piston 2 is driven against a chisel or other work element 6 at the front end of the barrel and supported therein by the usual bushing 7 20 as shown.

The handle for the tool is secured to the rear end of the barrel and comprises a coupling section 8 and a hand grasping section 9. The coupling section 8 is in the form of a cap having 25 a tubular or sleeve-like portion 10 which fits over the rear end of the barrel and has screw threaded connection therewith as at 11. This connection comprises internal screw threads in the sleeve 10 and external screw threads on the barrel 1. 30

A lock is employed at the forward end of the sleeve 10 to hold the handle assembly against rotation after being clamped on the barrel. The lock may comprise a ring 12 slidably, but non-rotatably, fitted on the barrel beyond the sleeve 35 10 and having teeth to interlock with teeth on the front end of the sleeve. A spring clip 13 engages the ring and the sleeve to hold their teeth interlocked.

The coupling section 8 encloses the valve block 40 3 and has an end wall 14 providing a shoulder 15 for direct contact with the valve block as shown. Thus the valve block may be tightly and solidly clamped against the barrel end by the coupling section 8 when the latter is screwed tightly on the 45 barrel. The metal to metal contact between the parts prevents leakage of the pressure fluid between them.

The cushioning means in accordance with my 50 invention, comprises a relatively flat ring or annulus 16 of solid resilient material such as live rubber. The member 16 is incorporated in the handle construction between the coupling section 8 and an auxiliary section 17. The latter has an externally screw threaded hollow lug or projec- 55

- tion 18 for connection with the hand grasping section 9 as shown. The section 9 has a threaded opening 19 to receive the lug 18. The opening 19 extends completely through the portion of the section 9 to which the section 17 is clamped and crosses the pressure fluid supply passage 20 therein as shown. A plug 21 is employed to key the handle section 9 to the lug 18 to hold these parts against rotation when assembled.
- 10 The cushion member 16 seats against the opposed, preferably flat surfaces of the handle sections 8 and 17 and is vulcanized thereto to secure these parts together. This connection is made before the handle assembly is applied to the barrel 1 and before all of the handle sections are assembled in handle forming relation. Thus only the handle sections 8 and 17 and the associated cushion member 16 need be handled in the vulcanizing operation and the latter can thus be performed with the least number of handle parts. This simplifies and reduces the cost of the vulcanizing operation and avoids the necessity of handling or making provision to accommodate any of the handle parts not essential to securing the cushion member 16 in place. Thus the larger hand grasping section 9 is not included in the vulcanizing operation and the parts 8, 16, and 17 may be connected together as a separate unit. This facilitates the manufacture and assembly 25 of the handle fixture and enables the cushion member to be incorporated therein with the least possible expense.
- 30 The cushion member 16 is provided with a depending ring-like flange 22. Said flange is integral with the cushion member 16 and fits in a central opening 23 in the end wall 14 of the coupling section 3. The flange 22 is vulcanized to the wall of the opening 23 when vulcanizing the cushion member to the sections 8 and 17.
- 35 The flange 22 is offset laterally from the central opening 24 in the cushion member to provide a recess for a metal ring 25 which preferably covers the inner surface of the flange 22 and is substantially flush with the wall of the opening 24 in the cushion member. The ring 25 is also vulcanized in place when vulcanizing the cushion member to the sections 8 and 17.
- 40 A tubular member 26 is pressed into the assembly after the cushion member 16 and the ring 25 have been vulcanized in place. The member 26 has a tight fit in the lug 18 and extends from adjacent the closed upper end of the lug above the passage 23 to the metal ring 25, passing through the opening 24 in the cushion member 55 16 as shown. The opening 24 is larger in diameter than the member 26 and the cushion member 16 is exposed on the outer side of the tool for lateral expansion under compression in opposite directions.
- 50 60 The member 26 extends into the ring 25 to convey the pressure fluid from the handle section 9 to the barrel of the tool and to compress the flange 22 on the cushion member 16 in response to bending the section 9 out of axial alignment with the barrel 1. Thus the cushion member 16 is relieved of side strains without reducing its cushioning effect and metal to metal contact with the lower end of the member 26 and chafing or wearing of the cushion flange is prevented in the 65 relative movement of the handle parts in response to a compression of the cushion member 16 by vibrations or axial bending of the section 9.
- 70 After the handle parts have been assembled a passage 27 is drilled into the handle section 9 in alignment with the supply passage 20 and

through the tubular member 26. This provides the member 26 with diametrically opposed ports, one 28 in register with the supply passage 20 and the other 29 in register with the drilled passage 27. A metal bushing 30 is pressed into the port 28 and the adjacent portion of the passage 20 to extend across the joint between the lug 18 and the handle section 9 to prevent leakage of the pressure fluid. The bushing 30 is sufficiently thin to readily shear off when the handle parts are disassembled for renewing the vulcanizing or otherwise.

75 The plug 21 is inserted into the passage 27 and into the port 29 to key the lug 18 to the handle section 9 whereupon a screw plug 31 is 15 screwed into the passage 27 to hold the key plug in place.

80 A sealing ring 32 of synthetic rubber overlaps the lower ends of the cushion flange 22 and the metal wear ring 25 to prevent lubricant in the barrel or entering with the incoming pressure fluid reaching the cushion member 16 to deteriorate or injure it. The sealing ring 32 is seated in an annular groove or recess 33 in the upper surface of the valve block 3 as shown in Fig. 1. 85 The sealing ring is clamped against the flange 22 and the ring 25 when the handle assembly is clamped on the barrel.

90 The cushion member 16 as well as the adjacent part of the handle section 17 and the upper 30 part of the sleeve 10 are made substantially hexagonal in shape as shown in Figs. 2 and 3. The purpose of this is to provide means by which the section 17 may be held by a wrench or in a vice while being screwed into the handle section 9. Similarly the sleeve 10 can be held when assembling and disassembling the barrel 1. Thus the cushion member is not strained or distorted when applying or removing the handle section 9 and barrel 1, respectively. Instead of a hexagonal contour, any other desired non-circular shape may be employed.

95 The handle section 9 has a nipple 34 or equivalent fixture for connecting the tool to a source of pressure fluid supply. Also the handle section 9 contains a throttle valve (not shown) for controlling the flow of pressure fluid through the handle to the tool. A trigger 35 is incorporated in the handle to control the opening and closing of the throttle valve.

100 The tubular member 26 registers with the main inlet port 36 in the valve block 3 so as to supply pressure fluid directly to the valve block. Moreover the valve block is spaced inward from the adjacent portion of the sleeve 10 to provide an 55 exhaust chamber 37 which connects with the atmosphere through one or more exhaust ports 38 in the sleeve 10. The barrel 1 has exhaust ports and passages connected with the chamber 37 as shown.

105 The cushion member 16 spaces the members 8 and 17 and completely fills all portions of this space occupied by the cushion member. The latter being of resilient material and solid throughout effectively absorbs and dampens vibrations to which the barrel 1 is subjected in the operation of the tool. Thus these vibrations are not transferred to the handle section 9 and the hand of the operator grasping said section in the use of the 70 tool is relieved of the sting and fatiguing jars as heretofore. Also the cushion member is free to expand laterally in opposite directions and thus is able to effectively respond to the vibrations referred to to dampen and absorb them. The cushion 75

ion flange 22 takes care of any bending or twisting of the handle section 9 out of axial alignment with the barrel 1 and thus relieves the main cushion member 16 of side strains without reducing its 5 cushion effect.

The details of construction and arrangement of parts shown and described may be variously changed and modified without departing from the spirit and scope of my invention, except as 10 pointed out in the appended claims.

I claim as my invention:

1. In a portable pneumatic hammer having a barrel, a cushioned handle secured to one end of the barrel, said handle comprising a hand 15 grasping section having a pressure fluid supply passage therein, a coupling section connecting the handle to the barrel, a third section carried by the hand grasping section, a cushion member of solid resilient rubber interposed between and vulcanized to the third and the coupling sections, respectively, for relieving the hand grasping section of vibrations in the operation of the tool, and a tubular member connected with the supply 20 passage in the hand grasping section and extending into the coupling section through the cushion member for conveying pressure fluid for operating the tool from the handle to the barrel, said cushion member maintaining the tubular member and third section out of contact with the 25 coupling section and being exposed on the outer side of the tool for expansion laterally of the barrel, said tubular member being carried by the third section, and the hand grasping section being releasably secured to the third section, whereby 30 the cushion member may be vulcanized to the third and the coupling sections while released from the hand grasping section.

2. In a portable pneumatic hammer having a barrel, a cushioned handle secured to the inner 40 end of the barrel, said handle comprising spaced sections, one section coupling the handle to the barrel and having an opening over the inner end of the barrel and the other section providing a hand grasping portion having a pressure fluid 45 supply passage therein, a cushion member of solid resilient rubber interposed between and vulcanized to said sections for relieving the hand grasping section of vibrations in the operation of the tool, and a tubular member connected with the 50 supply passage in the hand grasping section and extending into the opening in the coupling section through the cushion member for conveying pressure fluid for operating the tool from the handle to the barrel, said cushion member having an 55 integral portion surrounding the end of the tubular member in the opening in the coupling section for compression in response to bending of the hand grasping section out of axial alignment with the barrel.

3. In a portable pneumatic hammer having a barrel and a hammering piston therein, a valve block seated on the inner end of the barrel and having valve means for controlling the supply 60 of pressure fluid to the barrel for reciprocating the piston, a cushioned handle secured to the inner end of the barrel and comprising, a hand grasping section having a pressure fluid supply passage therein, a coupling section screwed on the barrel over and against the valve block for 65 clamping the same on the barrel, a third section releasably secured to the hand grasping section, a cushion member of solid resilient rubber interposed between and vulcanized to the third and coupling sections, respectively, for relieving the 70 hand grasping section of vibrations in the oper-

ation of the tool, and a tubular member connected with the supply passage in the hand grasping section and extending into the coupling section through the cushion member for conveying pressure fluid for operating the tool from the handle 5 to the barrel, said cushion member maintaining the tubular member and the third section out of contact with the coupling section and being exposed on the outer side of the tool for expansion laterally of the barrel, said tubular member being 10 carried by said third section.

4. In a portable pneumatic hammer having a barrel, a cushioned handle secured to one end of the barrel, said handle comprising a hand grasping section having a pressure fluid supply passage 15 therein, a coupling section connecting the handle to the barrel, a third section releasably secured to the hand grasping section, a cushion member of resilient rubber interposed between and vulcanized to the third and coupling sections, respectively, to absorb vibrations imparted to the coupling section from the barrel, a tubular member carried by the third section and extending into the coupling section through the cushion member, said tubular member being connected 20 with the supply passage for conveying pressure fluid from the handle to the barrel, said cushion member having an integral flange portion interposed between the tubular member and the coupling section and a wear resisting surface carried by the flange portion for the tubular member.

5. In a portable pneumatic hammer having a barrel, a cushioned handle secured to one end of the barrel, said handle comprising a hand grasping section having a pressure fluid supply passage therein, a coupling section connecting the handle to the barrel, a third section releasably secured to the hand grasping section, a vibration absorbing cushion member of solid resilient rubber 40 interposed between and vulcanized to the third and coupling sections, respectively, and a tubular member carried by the third section and extending into the coupling section through the cushion member, said tubular member being connected 45 with the supply passage for conveying pressure fluid from the handle to the barrel, said cushion member being exposed on the outer side of the handle and having its opening for the tubular member larger in diameter than the same, whereby 50 the cushion member may expand laterally of the barrel in opposite directions.

6. In a portable pneumatic hammer having a barrel, a cushioned handle secured to one end of the barrel, said handle comprising a hand grasping section having a pressure fluid supply passage 55 therein, a coupling section connecting the handle to the barrel, a third section having a hollow lug to which the hand grasping section is releasably secured, a vibration absorbing cushion member 60 of solid resilient rubber interposed between and vulcanized to the third and coupling sections, respectively, and a tubular member having a pressed fit in said lug and extending into the coupling section through the cushion member, said tubular member and said lug having communicating openings connected with the supply passage for conveying pressure fluid from the handle to the barrel through the tubular member.

7. In a portable pneumatic hammer having a barrel and a hammering piston therein, a valve block seated on the inner end of the barrel and containing a valve for controlling the supply of 70 pressure fluid to the barrel for reciprocating the 75

piston, a cushioned handle secured to the barrel over the valve block and comprising a hand grasping section having a pressure fluid supply passage therein, a coupling section connecting the handle to the barrel, a third section releasably secured to the hand grasping section, a vibration absorbing cushion member of solid resilient rubber interposed between and vulcanized to the third and coupling sections, respectively, a tubular member carried by the third section and extending into the coupling section through the cushion member, the latter being connected to the supply passage for conveying pressure fluid from the handle to the barrel, said cushion member having an integral flange portion between the tubular and cushion members, and means providing an oil seal between the valve block and

the adjacent ends of the flange and the tubular member.

8. In a portable impact tool having a barrel, a cushioned handle secured to one end of the barrel, said handle comprising a hand grasping section, a coupling section screwed on the barrel for connecting the handle thereto, a third section having screw threaded connection with the hand grasping section, and a cushion member of resilient rubber interposed between and vulcanized to the third and coupling sections, respectively, said third and coupling sections having wrench engaging portions, whereby said sections may be applied to and removed from the barrel and the hand grasping section without straining the cushion member.

FRITHIOF P. FORSS.
